UNITED STATES PATENT OFFICE.

ALEXANDER L. MUNRO AND HARVEY H. RUMPEL, OF MILWAUKEE, WISCONSIN, AS-SIGNORS TO SMITH ENGINEERING WORKS, OF MILWAUKEE, WISCONSIN, A CORPORATION OF WISCONSIN.

BABBITT-CASTING PROCESS AND MEANS.

Application filed February 14, 1924. Serial No. 692,625.

To all whom it may concern:

Be it known that we, ALEXANDER L. MUNRO and HARVEY H. RUMPEL, the former a citizen of the Dominion of Canada, and a 5 subject and servant of the King of Great Britain, and the latter a citizen of the United States, both residing at Milwaukee, in the county of Milwaukee and State of Wisconsin, have invented a certain new and useful 10 Improvement in a Babbitt-Casting Process and Means, of which the following is a specification.

Our invention relates to means and to a process for producing Babbitt bearings, and 15 particularly to a means for and a process of producing Babbitt bearings for use with crushers wherein a large shaft is surrounded by an elongated Babbitt sleeve which is virtually a thin skin of Babbitt metal between the shaft and the cylindrical surfaced member which surrounds it. Another object 20 is the production of an improved Babbitt bearing which will be durable and simple to install. Another object is the provision of 25 a method for pouring Babbitt bearings which will permit the use of a harder material than could have in the past been advantageously poured in such thin form. Other objects will appear from time to time 30 in the course of the specification and claims.

We illustrate our invention more or less diagrammatically in the accompanying drawings, wherein—

Figure 1 is a perspective view of our improved Babbitt mould or mandrel;

Figure 2 is a cross section on the line 2—2 of Figure 1, with the babbitt in position therein;

Figure 3 is a perspective view of the babbitt removed from the mould or mandrel; and

Figure 4 is a partial cross section through the Babbitt mandrel showing the casting of babbitts with a portion cut away for an oil channel, illustrating a variation in the formation of the key.

Like parts are illustrated by like characters throughout the specification and drawings.

A is one half a Babbitt mandrel or mould which is provided with outwardly projecting fins as at A¹, A¹ which are slotted along their edges for bolts as at A², A². A³, A³ are interior bolt holes.

B is the central core which may be centered within the shells A in any satisfactory manner, leaving a circular space B¹ between it and the mandrel which will correspond to the thickness of the Babbitt bearing. It is illustrated as expanded at B² to contact 60 the inner walls of the shell A, the expanded portion B² being provided with a number of peripheral air vents B³.

C, C are risers tapering downwardly toward the bottom of the mandrel and diametrically opposed. Extending inwardly through the mandrel shells are the connecting channels C¹, C¹ separated by the bridges C², C² through some of which pass the bolt holes A³. These channels enter the key 70 way C³.

D, D are taper pegs adapted to form holes in the completed babbitts and D¹ are bars inserted between the mandrel and the central core and aligned with said taper pegs, 75 and are adapted to separate the bearings being poured into a plurality of sections or staves. It will be understood that the taper pegs or bars may be integral. Applicants prefer to insert two of said peg and bar 80 assemblies between the central core and the mandrel, the pair being diametrically opposed and at points 90° removed from the key ways C³, but obviously the number of staves could be increased by increasing the 85 number of bars used, or spacing them at smaller intervals about the mandrel.

In the use of Babbitt bearings, for example with gyratory crushers, a pair of sleeves is frequently used, one of smaller diameter 90 being intermediate the shaft of the crushing head and the eccentric sleeve which surrounds it, and the other of larger diameter being between said eccentric sleeve and the outer bearing thereabout. In such case 95 to facilitate the passage of oil, the inner sleeve may be cut away about a portion of its circumference, some times to the extent of one-fifth of the entire circumference of the sleeve, one-half being taken, for example, from one semi-cylinder and the other half from the other. In casting semi-cylinders of this type, it is merely necessary to increase the dimensions of the bar D¹ on one side of the cylinder, as shown in Figure 4. 100

Whereas we have shown in Figure 1 the preferred form of Babbitt bearing wherein the key projects outwardly from the bear-

ing cylinder, it may, under some circumstances, be preferable to reverse the position of the key, having it project inwardly instead of outwardly, as shown in Figure 4.

- 5 Babbitt bearings of great length and diameter are used in heavy machinery, for example in crushing machinery. In the past it has been customary to build up such bearings with a large number of staves which 10 are easy to pour but difficult to insert in the machine and to adjust. Applicants have vastly simplified this practice by employing cylindrical bearings consisting of two semi-cylindrical portions. Each of these semi-cylindrical portions is kept in position by 15 an integrally cast key.

In pouring a stave of such extended surface and thinness, one of the problems met 20 is to provide a sufficiently hard Babbitt metal which will fill the entire casing before it hardens. The more freely flowing metals 25 of a larger lead content and with a smaller proportion of harder metals are not strong enough or wear resistant enough to give maximum efficiency. This problem has been 30 met by the use of a form of mandrel or shell or mould which permits of a very rapid diffusion of the molten metal. We employ a shell which may be formed of two semi-cylindrical segments which are bolted together about a center core and are so spaced therefrom as to leave a thin substantially cylindrical space between core and shell. In 35 the walls of the shell and at points diametrically opposed we provide a riser or pouring channel of large cross sectional area preferably tapered from top to bottom. Along the length of each of these risers we 40 provide a series of elongated pouring slits separated by bridges but forming a practically continuous inlet for the molten metal from top to bottom of the riser. These slits lead into a vertical groove in the shell which 45 serves to shape the externally projecting and integrally cast key of each Babbitt segment or stave.

This key space, in the pouring of the metal, assists greatly in permitting easy access of the molten metal and its ready flow 50 through the restricted portion of the mould, forming in effect a supplemental pouring passage almost continuous with the risers. As the metal is poured into the pouring gates at the top of the risers and aligned with 55 these key ways, it almost simultaneously enters the key way through the vertically aligned openings and flows laterally about the center core. The extension of the metal about the inner core is so rapid and so 60 nearly simultaneous that the tendency to harden and clog and fault is practically entirely eliminated. Babbitt metal with a relatively large copper content can be poured in this manner without premature hardening 65 and resultant fault.

The diffusion of metal in the mould is limited by the vertical bars D¹ and thus by one pouring and about a single core we simultaneously form the two semi-cylindrical staves necessary for the completed bearing. When 70 the metal has set and the shells or mandrel are separated, we have only to remove from the core the two staves. The risers being joined to the key by a series of thin vertically separated leaves, can easily be broken 75 or knocked off. The rough portions are then trimmed off and the staves are complete. There is no tendency whatever for air to trap in the bottom of the mould or for the metal which reaches the bottom of the mould 80 to harden faster than the metal which fills the top. The metal poured into the riser passages flows first into the bottom of the mould, although in fact the molten metal flows practically simultaneously into the 85 mould at all levels.

While we have shown a specific form of mandrel mould and sleeve with some modifications, it will be realized that many 90 changes in size, shape, number and disposition of parts might be made, and in the process of moulding, without departing from the spirit of our invention, and we therefore wish our description and drawings to be taken as in a large sense diagrammatic, and 95 not as rigidly limited to the specific form or forms shown.

We claim:

1. The process of forming thin walled cylindrical Babbitt bearings which consists in 100 introducing the molten metal into the mould substantially simultaneously at a plurality of levels along said mould.
2. The process of forming thin walled cylindrical Babbitt bearings which consists in 105 introducing the molten metal into the mould substantially simultaneously at a plurality of levels along said mould, at a plurality of points laterally spaced about said levels.
3. The process of forming thin walled cylindrical Babbitt bearings which consists in 110 introducing molten metal into the mould substantially simultaneously at a plurality of levels along a plurality of points spaced 115 along a vertical axis parallel to the axis of the mould.
4. The process of forming thin walled cylindrical Babbitt bearings which consists in 115 introducing molten metal into the mould substantially simultaneously at a plurality of levels along a plurality of points spaced along a plurality of vertical axes parallel to the axis of the mould.
5. The process of forming thin-walled substantially cylindrical Babbitt bearings with 125 projecting keys which consists in introducing the molten metal into the mould along said keys substantially simultaneously at a plurality of levels along said mould.
6. The process of forming thin-walled, 130

- multiple stave, cylindrical Babbitt bearings with keys projecting from the staves, which consists in introducing the molten metal into the mould along said keys substantially simultaneously at a plurality of levels along said mould, and limiting the lateral flow of the metal entering the mould along lines intermediate said keys.
7. The process of forming thin walled cylindrical Babbitt bearings which consists in introducing molten metal into the mould substantially simultaneously at a plurality of levels along a plurality of points spaced along a plurality of vertical axes, parallel to the axis of the mould, and limiting the lateral flow of the metal entering the mould along said vertical axes, intermediate said axes.
8. The process of forming thin walled, multiple stave, substantially cylindrical Babbitt bearings with keys projecting from the staves, which consists in introducing molten metal into the mould along said keys substantially simultaneously at a plurality of levels, and limiting the lateral flow of the metal entering the mould, along lines substantially mid-way between said keys.
9. The process of forming thin walled cylindrical Babbitt bearings which consists in introducing molten metal into the mould substantially simultaneously at a plurality of levels along a plurality of points spaced along a pair of diametrically opposed vertical axes, parallel to the axis of the mould, and limiting the lateral flow of the metal entering the mould along said vertical axes, along a line substantially mid-way between said axes.
10. The process of pouring a Babbitt bearing, which consists in providing an outer shell, positioning an inner shell therewithin, to leave a substantially cylindrical space between the outer and inner shell, placing a pair of diametrically opposed longitudinal separations between and from end to end of said inner and outer shell, and introducing molten metal substantially simultaneously from end to end of said shell along diametrically opposed vertical axes, mid-way between said vertical separations.
11. In a mould for Babbitt bearings, a substantially cylindrical core, a containing shell spaced therefrom and having an inner surface substantially concentric therewith, said shell being penetrated by a plurality of substantially vertical inlet passages and by a plurality of connections between said vertical passages and the interior of said shell.
12. In a mould for Babbitt bearings, a substantially cylindrical core, a containing shell spaced therefrom and having an inner surface substantially concentric therewith, said shell being penetrated by a plurality of substantially vertical inlet passages and by a plurality of spaced, elongated slits between said vertical passages and the interior of said shell.
13. In a mould for Babbitt bearings, a substantially cylindrical core, a containing shell spaced therefrom and having an inner surface substantially concentric therewith, said shell comprising a plurality of sections, and means for securing them about the core, said shell being penetrated by a plurality of substantially vertical inlet passages and by a plurality of connections between said vertical passages and the interior of said shell.
14. In a mould for Babbitt bearings, a substantially cylindrical core, a containing shell spaced therefrom and having an inner surface substantially concentric therewith, said shell being penetrated by a plurality of substantially vertical inlet passages and by a plurality of connections between said vertical passages and the interior of said shell, the inner surface of said shell being vertically grooved to form a projecting key for the finished bearing, said groove being penetrated by said connections.
15. In a mould for Babbitt bearings, a substantially cylindrical core, a containing shell spaced therefrom and having an inner surface substantially concentric therewith, said shell being penetrated by a plurality of substantially vertical inlet passages and by a plurality of spaced, elongated slits between said vertical passages and the interior of said shell, the inner surface of said shell being vertically grooved to form a projecting key for the finished bearing, said groove being penetrated by said slits.
16. In a mould for Babbitt bearings, a plurality of opposed mould elements comprising a substantially cylindrical core, and a containing shell spaced therefrom, and having an inner surface substantially concentric therewith, said shell being penetrated by a plurality of substantially vertical inlet passages and by a plurality of connections between said vertical passages and the interior of said shell, one of said opposed mould members being vertically grooved to form a projecting key for the finished bearing, said groove being aligned with said vertical passages.

Signed at Milwaukee, Wisconsin, this 8th day of February 1924.

ALEXANDER L. MUNRO.
